OF ONE-THIRD TO SAID BREZIN, ONE-THIRD TO SAID BERZON, AND ONE-THIRD TO
WILLIAM KOSAKOFF, OF PHILADELPHIA, PENNSYLVANIA.

BAG FASTENER.

Application filed July 14, 1921. Serial No. 484,534.

To all whom it may concern:

Be it known that we, JOSEPH BREZIN and LOUIS BERZON, citizens of the United States, residing at Philadelphia, county of Philadelphia, and State of Pennsylvania, have invented a new and useful Improvement in Bag Fasteners, of which the following is a full, clear, and exact description, reference being had to the accompanying drawings, 10 which form a part of this specification.

Our invention relates to bag fasteners of the type used more especially in connection with hand bags.

Our invention has as its primary object 15 the provision of a fastener which may be readily unfastened to permit of the separation of the overlapping frame members of a bag and which when the members are separated will be automatically positioned to 20 fasten the members together again in the closing of the bag.

Further objects of our invention are to provide a fastener which will be efficient in operation and so constructed as to comprise 25 a minimum of parts, which may be readily assembled without the use of tools, and which when assembled will be proof against derangement and failure in operation.

Heretofore the known types of bag fasteners have been open to the objection that if 30 they were so constructed as to be unfastened and remain unfastened until the bag was opened, it was necessary to fasten them when the bag was shut, or if, on the other hand, they were so constructed as to fasten 35 by the mere shutting of the bag, it was necessary to positively hold them in unfastened position until the bag was opened. Either form of fastener is unhandy and 40 troublesome to the user, as in the first case fastening of the bag is frequently neglected, and in the second case opening of the bag is rendered difficult by the fact that it is necessary in the ordinary bag to maintain 45 two fasteners in unfastened position while the fastener incorporated with the lock is unfastened and in order to open the bag all three must be simultaneously maintained unfastened.

50 In accordance with our invention, the above described objections and difficulties are eliminated and a bag equipped with our fasteners may be readily opened and when closed will be securely fastened with only

the necessity of merely unfastening the fasteners which then remain unfastened until the bag is opened, whereupon they are automatically prepared to securely fasten the bag when it is again closed, all of which will appear more fully hereinafter.

Having now indicated in a general way the nature, purpose and advantages of our invention, we will proceed to a detailed description thereof, with reference to the accompanying drawings in which we have 65 illustrated a preferred embodiment, and in which—

Fig. 1 is a view of the upper portion of a bag with fasteners embodying our invention attached.

Fig. 2 is a side elevation of a fastener embodying our invention.

Fig. 3 is a sectional view of the fastener.

Fig. 4 is a section on line 4—4 Figure 3.

Fig. 5 is a longitudinal sectional view of 75 the fastener in fastening position.

Fig. 6 is a longitudinal view similar to that of Figure 5 with the fastener in unfastened position.

Fig. 7 is an elevation of a modification of 80 a detail of the fastener.

The casing *a*, provided with a slot *b* in one of its end walls, is secured to the overlying frame *c* of the bag *d* by means of lugs *e*, which extend through suitable slots in the 85 frame and are bent over as shown in Figure 5. The casing *f* is provided with side walls having elongated slots *g*, *g* near their lower edges and having their upper edges bent outward and downward to form L-shaped 90 flanges *h*. The end walls of the casing *f* are made of less height than the side walls. The casing *f* is adapted to be secured within the casing *a* by means of lugs *i* which extend from the side walls of casing *a* and are bent 95 upwardly to engage the L-shaped flange *h* on casing *f*, as shown in Figure 3.

Within the casing *f* is positioned a locking member *j* having a flange *k*, provided with cam surfaces *m*, *m'* at opposite ends, 100 extending from its upper edge and provided with a downwardly extending bolt member *n* having its lower edge bevelled as at *o* and adapted to engage the bolt receiver *p* carried by the underlapping bag frame 105 member *q* and which, when the bag is closed, extends through the slots *g*, *g* as shown in Figure 3. The bolt receiver *p* is provided on

one side with a lateral extension u , the edges of which are bevelled as shown in Figure 4.

Positioned within the casing f adjacent to the locking member j is the bolt controlling member r having downwardly extending legs v provided on its upper edge with a flange s adapted to underlie the flange k on locking member j and having at each end cam surfaces r', r' complementary to the 10 cam surfaces m, m' . An extension t extends from flange s , above the top of the end wall of casing f , and through the slot b in casing a , and forms a finger piece, whereby the controlling member may be moved relatively 15 to the locking member and through the action of the cam surfaces m, m and r', r' effect a raising or lifting of the locking member j .

The flat bow spring w rests on the flange k 20 of the locking member with its ends bearing against the under side of the top of casing a and acts to tend to keep the locking member in lowered or locked position.

In practice, assuming the bag to be closed, 25 the various parts will be in the position shown in Figures 3 and 5. If now it is desired to open the bag, the extension t is pressed and the bolt controlling member moved relative to the locking member. The 30 action of cam surfaces r, r' and m, m' causes the locking member to be raised against the action of spring w , the bolt n is freed from the receiver p and the parts assume the position shown in Figures 4 and 6. The bag 35 may now be opened and as the receiver p is withdrawn the extension u contacts with one of the legs v of the controlling member, causing it to return to normal position and permit the locking member to assume its 40 normal locking position under the influence of the spring w . When the bag is again closed, the receiver striking the bevelled edge of the bolt lifts it, and when the bag is fully closed the bolt drops into the receiver. 45

In Figure 7 is disclosed a modified form of controlling member comprising a round

member s' adapted to underlie the flange k on the locking member and provided at one end with an extension t' forming a finger 50 piece. Secured to the member s' is an L-shaped extension v' which, on the opening of the bag, is engaged by the extension u on the bolt receiver to return the controller to normal position and permit the bolt to 55 be lowered by spring w .

Having now fully described our invention, what we claim and desire to protect by Letters Patent is:—

1. A bag fastener comprising a bolt receiver, a locking member adapted to engage said receiver to lock a bag, a spring adapted to act on said locking member and yieldingly retain said member in locking position, a controlling member, complementary cams 65 on said locking member and controlling member adapted, when said controlling member is shifted relative to said locking member, to move and hold said locking member out of locking position, and a cam 70 carried by said receiver acting, when said bag is opened, to shift said controlling member to permit said locking member to return to locking position.

2. A bag fastener comprising a bolt receiver, a spring tensioned locking member adapted to be snapped into interlocking engagement with said receiver to lock a bag, a controlling member in engagement with said locking member and adapted to be manually 80 shifted to move and hold said locking member out of locking position, and a cam carried by said receiver adapted, when the bag is opened, to engage and shift said controlling member to permit said locking member 85 to return to locking position whereby, when said bag is closed, said locking member will snap into engagement with said receiver.

In testimony of which invention, we have hereunto set our hands, at Philadelphia, Pa., 90 on this 11th day of July, 1921.

JOSEPH BREZIN.
LOUIS BERZON.
